UNITED STATES PATENT OFFICE

2,494,405.

CENTRIFUGAL MOLD AND LINER
THEREFOR

Ernest R. Olsen, Rudolph F. Flora, and Clifford J. Lonnec, Muskegon, Mich., assignors to Hastings Manufacturing Company, Hastings, Mich.

Application November 18, 1946; Serial No. 710,450

6 Claims. (Cl. 22—113.5)

1.

This invention relates to improvements in a mold liner.

The principal objects of this invention are:

First, to provide a liner for a permanent centrifugal mold having insulating properties for protecting the mold and which presents a continuous smooth surface for the casting of metal therein.

Second, to provide a liner for a permanent centrifugal mold which may be formed out of sheet asbestos and with a smooth surface which will not form ridges on a casting formed therein.

Third, to provide means for securing the longitudinal edges of a sheet asbestos liner in flush abutting relationship to form a substantially continuous casting surface for a tubular mold.

Other objects and advantages pertaining to the details and economies of the invention will be apparent from the following description and claims.

The drawings, of which there is one sheet, illustrate a permanent centrifugal mold and four forms of liner cooperable therewith to form an insulating casting surface.

Fig. 1 is a perspective view of the mold with a preferred form of the liner therein.

Fig. 2 is a fragmentary perspective view partially in cross section showing the joint in the liner illustrated in Fig. 1.

Fig. 3 is a fragmentary perspective view partially in cross section of a modified form of clamping means for the liner illustrated in Figs. 1 and 2.

Fig. 4 is a perspective view of a further modified form of clamping means for a liner.

Fig. 5 is a perspective view of a modified form of liner.

Fig. 6 is a fragmentary perspective view of the clamping strip shown in Fig. 3.

Fig. 7 is a fragmentary cross sectional view showing in greater detail the joint between the edges of the liner shown in Fig. 4.

Reference is made to our copending application for Method and apparatus for making centrifugal castings, Serial No. 696,877, filed September 13, 1946, in which is disclosed a ventilated permanent centrifugal mold member lined with a liner of sheet asbestos or other heat resistant material which protects the surface of the casting from becoming chilled by the walls of the mold and which renders the casting easily removable from the mold by sliding from the mold along with the casting. This prior lining is freely supported in the mold and has unconnected ends so that in use a fine ridge of metal escapes

2.

through the joint between the edges of the liner and becomes chilled against the wall of the mold. The present invention provides a liner operable in molds similar to that disclosed in the above-mentioned application and in our copending application for Centrifugal mold and liner, Serial No. 710,449, filed November 18, 1946, which presents a substantially smooth and continuous surface to the molten metal poured in the mold and from which no metal can escape to form a ridge on the castings.

As is shown in the drawings, the permanent mold member 4 is provided with a plurality of longitudinally extending ventilating grooves 2 along the inner surface thereof and a relatively wide and shallow groove 3. The mold 4 is designed to operate in a centrifugal molding machine similar to that disclosed in the above-mentioned application, Serial No. 696,877.

20 Positioned within the mold 4 is a liner 4 which is preferably formed of sheet asbestos or some similar heat resisting material having its longitudinal edges 5 brought into closely abutting and smoothly aligned relationship. A sealing strip 6 is secured to the outer sides of the edges 5 as by a suitable adhesive 7 and the tubular liner thus formed is positioned in the mold with the sealing strip positioned in the shallow groove 3 in the mold wall. The sealing strip 6 may be in the form of a metal band or may consist of a strip of asbestos similar to the body of the liner.

When molten metal is cast in the mold and liner just described the surface of the casting will be substantially smooth and continuous, there being no space for it to escape between the edges 5 of the liner. The insulating properties of the asbestos liner will prevent the casting from becoming chilled and hardened and will at the same time protect the surface of the permanent mold 4 from becoming burned and cracked. The casting thus formed may be easily removed from the mold since the liner will adhere to the casting and slide easily on the inner surface of the mold.

45 Figs. 3 and 6 illustrate a liner 4 which is the same in all respects as the liner shown in Fig. 1 except the sealing strip 6A is in the form of a metal band having inwardly turned teeth 8 formed along the edges thereof and knock-in prongs 9 formed in the body of the band which are arranged to pierce and be crimped around the edge portions of the liner by a suitable pressing machine and mandrel similar to a stapler, not shown, to tightly clamp the longitudinal edges 5 of the liner together.

Fig. 5 illustrates a modified form of liner 4B having its longitudinal edges cut along mating interlocking wavy lines 5B. The two edges of the liner are secured together prior to insertion in the mold by a series of stitches 10 which are formed by a suitable sewing machine. The stitches are preferably formed with an asbestos fiber thread or a fine metallic wire.

Figs. 4 and 7 illustrate a further modified form of liner 4C in which the longitudinal edges 5 are secured together by a series of staples 11 driven inwardly from the outside of the tubular liner and crimped around in the body of the liner by a suitable mandrel, not shown.

In all forms of the liner illustrated the abutting edges of the liner material are firmly held in tightly engaged and aligned relationship to provide a substantially continuous inner surface for the liner. Thus relatively inexpensive and commercially standard sheet material may be used for forming the liners and a continuous casting surface may still be obtained. All of the liners function as set out above to improve the quality of the castings formed in the mold by preventing chilling of the castings and to speed up the casting operation by rendering the castings easily removable. The liners further conform accurately in contour to the shape of the tubular mold and do not bulge inwardly into the mold cavity.

We have described several practical forms of sealed and flush joint liners so that others skilled in the art may reproduce the same or minor modifications thereof without further description.

Having thus described our invention, what we claim as new and desire to secure by Letters Patent is:

1. Casting apparatus comprising a permanent rotatable undivided tubular mold having a plurality of longitudinally extending ventilating grooves formed on the inner surface thereof and a widened groove formed on said inner surface, a liner of sheet heat resistant material positioned in said mold and in closely supported facing relationship with the surface thereof, the longitudinal edges of said liner being closely abutted and disposed in front of said widened groove, and a joining member securing said edges together and positioned in said widened groove.

2. Casting apparatus comprising a permanent rotatable undivided tubular mold having a longitudinally extending groove formed on its inner surface, a liner of sheet heat resistant material positioned in said mold and in closely supported facing relationship with the surface thereof, the longitudinal edges of said liner being closely abutted and disposed in front of said groove, and a joining strip securing said edges together and positioned in said groove.

3. Casting apparatus comprising a permanent rotatable undivided tubular mold having a plurality of longitudinally extending ventilating grooves formed on the inner surface thereof and a relatively wide and shallow groove formed in said surface, a liner of sheet heat resisting material positioned in said mold in closely supported facing relationship with the surface thereof, the

longitudinal edges of said liner being in closely abutted relationship and disposed in front of said shallow groove, and a sealing strip of metal having inwardly pressed teeth on the edges thereof and knock-in prongs in the body thereof positioned in said shallow groove with said teeth and prongs in clamping engagement with said liner to hold said edges together.

4. Casting apparatus comprising a permanent rotatable undivided mold having a ventilated mold wall surface and a relatively wide longitudinal groove formed in said surface, a liner of sheet heat resisting material positioned in said mold in closely supported facing relationship with the surface thereof, the longitudinal edges of said liner being in abutting relationship and disposed in front of said groove, and a joint strip in retaining engagement with said liner to hold said edges together.

5. Casting apparatus comprising a permanent rotatable undivided mold having a ventilated mold wall and a groove formed in its mold wall surface, a liner of sheet heat resisting material positioned in said mold in closely supported facing relationship with the surface thereof, the longitudinal edges of said liner being in closely abutted relationship and disposed in front of said groove, and a joint strip on the outer side of the liner covering the joint thereof, said groove being adapted to receive said joint strip.

6. Casting apparatus comprising a permanent rotatable undivided tubular mold having a longitudinal groove in its mold wall surface, a liner of sheet heat resisting material positioned in said mold in closely supported facing relationship with the mold wall surface thereof, the longitudinal edges of said liner being in closely abutted relationship and disposed in front of said groove, and a joint strip in retaining engagement with said liner to hold said edges together, said groove being adapted to receive said joint strip.
